HANGER

Filed Feb. 20, 1928

Inventor.
Benjamin H. Carpenter
by Arthur J. Randall, Atty.

UNITED STATES PATENT OFFICE

BENJAMIN H. CARPENTER, OF ROXBURY, MASSACHUSETTS

HANGER

Application filed February 20, 1928. Serial No. 255,519.

My invention relates to connecting links or hangers by means of which pipes and other things are connected or are suspended from an overhead support and it has for 5 its object to provide an improved article of this class and particularly to provide an improved pipe hanger.

To these ends I have provided a very inexpensive and efficient connecting link or 10 hanger of the class indicated which can be produced with ease and dispatch from certain standard stock.

My improved hanger comprises a bar of metal having provision at one end for attachment to one object and having its opposite end portion bent back upon the body portion thereof to form an eye for engaging another object, said bent back end portion being locked to the body portion by a link 20 or band directly embracing the two which, in the best form of my invention, may be an ordinary washer. In one form of my invention both end portions of the metal bar are bent back upon the body portion there- 25 of and secured in their bent back positions by one or more bands or washers encircling said bent back portions and said body portion. Other features of my invention are hereinafter pointed out.

30 In the accompanying drawings.

Figure 1 is a side elevation of a pipe hanger constructed in accordance with my invention.

Figure 2 is a front view of the pipe hanger, shown in Fig. 1.

Figure 3 is a section on line 3—3 of Fig. 1.

Figure 4 is a perspective view of the bar of stock from which one of the elements of the hanger, shown in Figs. 1 and 2, is 40 produced.

Figure 5 illustrates another form of my invention.

Figure 6 is a view of the rod from which one of the elements of the link or hanger, shown in Fig. 5, is constructed.

Figure 7 is a section taken on line 7—7 of Fig. 5.

In making the pipe hanger, shown in Figs. 1 and 2, a section of flat metal strip stock is cut from a strip, such as shown in

Fig. 4, to the desired length. When the device is to be used as a pipe hanger and is to be connected with an overhead beam such as 2, Figs. 1 and 2, one end portion of this section of metal strip, shown at 1 in Figs. 1 and 2, is bent around the beam 2 as at 3 and 4 to provide an eye or loop surrounding beam 2, and then a link or washer member 6 is slid on to the strip 1 from the lower end thereof upwardly into a position where it encircles the end portion 5 of the strip 1 which latter will, at that time, occupy the dotted line position in Fig. 1, after which said end portion 5 is bent upwardly away from the body portion 7 of the strip 1 so as to lock the washer in its holding position. Another link or washer member 8 is then threaded on to the strip 1 and maintained in an elevated position, such as that indicated by dotted lines in Fig. 1, while the lower end of the strip or bar 1 is bent around the pipe 9 that is to be supported as indicated at 10, so that its extreme end portion 11 occupies a position alongside of the body portion 7 as indicated by dotted lines in Fig. 1. The washer 8 is then lowered as far as possible after which the extreme end portion 11 of the strip is bent outwardly and downwardly away from the body portion 7 to thereby lock the washer 8 in its holding 80 position.

From the above description it will be clear that a workman can equip himself with a quantity of the strip metal shown in Fig. 4 and a number of washers 6 or 8 and quickly 85 install any number of pipe hangers, cutting up the strip into the desired lengths as the hangers are made and installed. It will thus be clear that the cost of each pipe hanger, including material and labor, is very 90 small.

In the form of my invention shown in Fig. 5 the link or hanger is produced from round bar stock 12, Fig. 6. A section of this bar stock 12 of the desired length is cut off and threaded at one end, as illustrated at 13, Fig. 5. An interiorly threaded insert socket 14 is incorporated in a concrete ceiling 95 15 and this insert socket 14 may be made at its upper end with a flange or the like 15 100

which securely anchors the socket within the material of the ceiling. After engaging the threaded end of the rod with the socket 14 the lower end portion 16 is bent back upon the body portion 17 to form a pipe engaging eye or loop 18. This loop or eye 18 is formed after positioning a washer 19 on the upper part of the body portion 17 and then after this washer has been moved down into position shown in Fig. 5 the extreme end portion 20 of the bar is bent outwardly to lock the washer in its holding position.

While the device above described is primarily intended for use as a pipe hanger it should be obvious that when completed it serves as a connecting link between two objects and it will be understood that such a link is adapted for use in many other situations.

What I claim is:

A device for connecting two objects, said device comprising a comparatively stiff bar of metal having provision at one end thereof for attachment to one of said objects and having its opposite end portion bent back upon the body portion thereof to form an object engaging eye, and a link embracing and directly engaging said body portion and said bent back end portion to lock the same together, the extremity of said bent back end portion beyond the link being free but bent laterally away from said body portion to lock the link in operative position where it is held by the inherent stiffness of said laterally bent extremity.

Signed by me at Boston, county of Suffolk and State of Massachusetts, this 4th day of February, 1928.

BENJAMIN H. CARPENTER.
